UNITED STATES PATENT OFFICE.

JACOB SIEGEL, OF PHILADELPHIA, PENNSYLVANIA.

WEARING APPAREL.

Application filed August 28, 1925. Serial No. 52,519.

To all whom it may concern:

Be it known that I, JACOB SIEGEL, a citizen of the United States, and a resident of the city and county of Philadelphia, State of Pennsylvania, have invented certain new and useful Improvements in Wearing Apparel, of which the following is a specification, reference being had to the accompanying drawing.

10 My invention relates particularly to the means employed for attaching the facing of a coat to the coat body, and is especially directed to the means of attachment at the region of the pocket.

15 In the manufacture of coats in general, but having reference in particular to that class of coats commonly known as overcoats or top coats, it has been common practice to attach the flap comprising the bellows 20 facing to the material forming the coat body at the region of intersection of the inner edge of the facing and the lower edge of the lining, by hand felling and tacking, the latter being required to pass through several 25 thicknesses of material, which produces a thick impression on the outside of the coat body, and so tends to cause such breakage as to destroy the continuity of the material forming the coat body and thereby produce 30 an unsightly crease or wrinkle.

The principal objects of my invention are to provide means for attaching the coat facing to the coat body that will not only avoid the thick impression and consequent crease 35 or wrinkle but will eliminate the necessity of hand felling or tacking.

Other objects of my invention are to provide in a coat a load carrying structure which, in effect, tends to serve as a strut or 40 truss, tending to so equalize the stresses incident to the pockets being supported by the depending skirt of the coat structure as to prevent any tendency to draw or drag the material forming the coat body.

45 Further objects of my invention are to provide a coat facing with means for attaching it to a coat body, which is so formed and arranged as to be capable of attachment by a single and continuous machine stitching operation.

Specifically stated, the form of my invention hereinafter described comprehends a coat having a facing and attached lining terminating in the region of the coat pocket 55 and having means affording an attachment for the coat body and its facing and lining

comprising a flap or bellows facing terminating at the intersection of the inner edge of the facing and lower edge of the lining in a substantially right-angled formation 60 and in the angle of which is attached to the facing lining a right-angled triangular gusset forming in effect an angle plate serving as a truss or brace arranged to compensate for the come and go movements of the skirt 65 of the coat body.

My invention further includes a triangular gusset so folded as to embrace a reinforcement arranged to stiffen it and thereby increase its effective bracing tendencies. 70

My invention also includes all of the various novel features of construction and arrangement as hereinafter more definitely specified.

In the accompanying drawings Fig. 1 is a 75 fragmentary inside elevational view of a coat having an inside pocket and conveniently embodying my invention; Fig. 2 is an elevational view of the facing, lining and pocket backing assembly as it appears before being attached to the coat body as shown in Fig. 1, and showing the reverse face from that shown in said figure; Fig. 3 is a fragmentary inside elevational view of a coat having 80 an outside patch pocket and conveniently embodying my invention; Fig. 4 is an elevational view of the facing and lining assembly as it appears before being attached to the coat body shown in Fig. 3; Fig. 5 is a 85 fragmentary perspective sectional view of the region of the coat including the reinforcement; Fig. 6 is an enlarged transverse sectional view taken horizontally through the coat body, its facing and facing attachment on line 6-6 in Fig. 1; Fig. 7 is a face view of the facing attachment of gusset extended in plane; Fig. 8 is a perspective view of said gusset folded on the diagonal into triangular form; Fig. 9 is a perspective 100 view of the gusset folded as shown in Fig. 8 but showing a reinforcing web interposed between the wings of said gusset; and Fig. 10 is a face view of the reinforcing web per se which is shown in Fig. 9. 105

In said figures the coat structure as shown in Figs. 1 and 2 comprises the body 1, facing 2, lining 3 and inside patch or pocket backing 4. The facing is provided with the usual means of attachment comprising the facing bellows flap 5 extended along the inner edge of the facing 2, being engaged with 110

said facing by the line of stitches 6 and having the folded back flange 7 forming the free edge 8 which is to be engaged with the coat body 1 by blind stitches 9 in a usual 5 and well known manner, as shown in Fig. 5.

Similarly the pocket patch or pocket backing 4 is provided with the bellows flap 10 having the folded back flange 11 forming the free edge 12, which is arranged to be 10 engaged with the coat body 1 by the blind stitching usually employed, being the same as the blind stitches 9, shown in Fig. 5.

The bellows flaps 5 and 10 terminate at their intersection as at 13 or at the region 15 where the lower edge of the inside pocket patch or backing 4 intersects the rear edge of the facing 2, and where, as before stated, it was heretofore necessary to continue the blind stitching by hand felling and by tacking 20 through several thicknesses of material including the coat body.

In order to obviate the necessity of hand felling or tacking I provide a triangular stress-carrying gusset 15 which in effect 25 serves as a strut or truss which may be engaged by blind stitches 16, which form a continuation of the blind stitching of the pocket bellows flap 10 and the blind stitching of the facing bellows flap 5, so that obviously 30 the blind stitching may be performed by a continuous or uninterrupted operation down the rear and lower edges of the pocket patch 4, then along the diagonal edge of the gusset 15 and continued 35 down the inner edge of the facing 2.

The coat structure shown in Figs. 3 and 4 is of the type having an outside patch pocket and therefore does not embody the inside pocket patch or backing. In this 40 style of coat the attaching device comprising the gusset 15' is disposed in the angle formed by the intersection of the rear edge of the facing 22 and the lower edge of the lining 23 and is secured to the material 45 forming the body 21 of the coat by blind stitches 17 which may be continuous with blind stitching extending along the lower edge of said lining 23 and along the diagonal edge of said gusset, and down the edge 50 28 of the flap 25 which is attached to the facing 22 by stitching 26 and has the folded back flange 27 forming the edge 28.

As shown in Fig. 7 the triangular gussets 15 and 15' may be best formed from a substantially square piece of fabric or webbing 55 30 which may be folded upon the diagonal indicated by the dot and dash line 31 to provide the triangular structure shown in perspective in Fig. 8, in which the wings 60 32 and 33 are slightly separated for convenience of illustration but which wings may be brought flat together to provide the gusset 15 shown in Figs. 1 and 2, or the gusset 15' shown in Figs. 3 and 4.

Although ordinarily the gusset formed as

shown in Fig. 8 may be found adequate, it might be deemed advisable in some classes of clothing to provide the gusset with a reinforcing web of buckram 35 which may preferably be inserted between the wings 32 70 and 33 as shown in Fig. 9, and which as shown separately in Fig. 10 is of triangular form so as to conform to the shape of the gusset when folded and be stitched together with the wings 32 and 33 thereof. 75

My invention is advantageous in that the stresses incident to the relative differences in the weight of the body material of the coat and the composite structure forming the inner fabric thereof are, by its employment, more evenly distributed over a line of stitching which more nearly conforms to a linear path, there being no sharp angular corners such as the right angular corner in the practice heretofore employed. Furthermore, the stitching between the acute angles of the triangular gusset extends obliquely and as the natural stresses tend in a downward direction they cut the diagonal stitching at an angle and at relatively different horizontal planes and consequently there is not the same tendency to pucker the attached material of the coat body as if they cut the horizontal line of stitching. 85

It will also be obvious that by reason of the fact of the shorter and relatively horizontal and vertical sides of the gusset being respectively attached to the inner composite structure of the coat by stitching 18 and 19 Fig. 5 and the longer diagonal side 100 being attached to the material forming the outer fabric or body of the coat, there is permitted a free come and go movement of the inner and outer fabrics without restriction to a point of contact as heretofore constructed. 105

I do not desire to limit my invention to the precise details of construction and arrangement as herein set forth as it is obvious that various modifications may be 110 made therein without departing from the essential features of my invention as defined in the appended claims.

Having thus described my invention, I claim:

1. A garment of the class described, comprising an outer fabric structure, an inner fabric structure arranged to be engaged with said outer fabric structure and having an interior angular corner therein, and a triangular reinforcement disposed in the angle of said corner and secured to the inner and outer fabric structures respectively. 115

2. A garment of the class described, comprising an outer fabric structure, an inner fabric structure arranged to be engaged with said outer fabric structure and having an angular corner formed therein, and a triangular reinforcement disposed in the angle of said corner and having two of its sides 120

secured to said inner fabric structure and its free side secured to said outer fabric structure.

3. A garment of the class described, comprising an outer fabric structure, an inner fabric structure arranged to be engaged with said outer fabric structure and having an open angular corner formed therein, a triangular reinforcement disposed in the angle 10 of said corner and having two of its sides secured to said inner fabric structure, and means for engaging said inner fabric structure with said outer fabric structure comprising stitches extending along the edges of 15 said angular opening and the free diagonal edge of said reinforcement.
4. A garment of the class described, consisting of an outer fabric structure and an inner composite fabric structure comprising a lining and facing respectively having their lower and rear edges intersecting to form an angular corner, a reinforcement in the form of a triangular gusset disposed in the angle 20 of said corner and having two of its side edges engaged with said lining and facing, and means for engaging said inner fabric structure to said outer fabric structure comprising stitches extending horizontally along 25

the lower edge of said lining, diagonally along the free edge of said reinforcement 30 and vertically along the inner edge of said facing.

5. A garment of the class described, consisting of an outer fabric structure, and an inner composite fabric structure comprising 35 a lining, a pocket backing forming a continuation of said lining and a facing, the respective lower and rear edges of the backing and lining intersecting to form an angular corner, a triangular gusset disposed 40 in the angle of said corner and having two of its marginal edges engaged with the inner fabric structure and the other edge engaged with the outer fabric structure.

6. An inner fabric structure for a garment 45 of the class described, comprising a facing and lining having their edges intersecting to form an angular corner and a triangular gusset disposed in said corner and having two of its edges secured to said inner fabric 50 structure and the third edge adapted to be secured to the outer fabric structure.

In witness whereof, I have hereunto set my hand this 24th day of August, 1925.

JACOB SIEGEL.
